UNITED STATES PATENT OFFICE.

ARTHUR J. WADSWORTH, OF WASHINGTON, DISTRICT OF COLUMBIA,
ASSIGNOR OF ONE-HALF TO FREDERICK W. BAXTER, OF WASH-
INGTON, DISTRICT OF COLUMBIA.

KEYBOARD FOR MONOTYPE PERFORATING-MACHINES.

No. 835,993.

Specification of Letters Patent.

Patented Nov. 13, 1906.

Application filed July 14, 1906. Serial No. 326,260.

To all whom it may concern:

Be it known that I, ARTHUR J. WADSWORTH, a citizen of the United States, residing at Washington city, in the District of Columbia, have invented a new and useful Improvement in Keyboard for Monotype Perforating-Machines, of which the following is a specification.

My invention is in the nature of an improved keyboard for monotype perforating-machines of the general character set forth in the patent to T. Lanston, No. 654,115, July 17, 1900.

This machine is designed to produce perforated record-strips or controllers which are subsequently used to govern other mechanism, such as type-making machinery in the production of printing-type.

In the monotype-keyboard the work of the operator on the keys is transmitted pneumatically to punches making perforations in a ribbon of paper feeding automatically through the machine from a continuous roll. The bank of keys is so constructed that the plunger of each key constitutes a valve. When any key is depressed, its plunger passes downwardly through a casing into a compressed-air chamber. Within the casing are formed passage-ways, one for each longitudinal and one for each transverse row of keys, and they are so arranged that a key-plunger passes through the casing at each intersection of a vertical and a horizontal passage-way. The key-plunger is adapted when depressed to receive compressed air from the said air-chamber and deliver it into the two passage-ways at the intersection of which it stands, whence it passes through pipes to the punch-operating mechanism.

Each longitudinal row of keys has a corresponding punch, and a punch is likewise provided for each transverse row, and the depression of any key will therefore operate the two punches representing, respectively, the longitudinal row and the transverse row in which it stands. The relative positions of the two perforations made by the simultaneous operation of the two punches determines the letter or character to be made when the paper ribbon is subsequently fed through the type-casting machine.

My invention relates to the keyboard of this machine, and has for its object to simplify and cheapen the construction of the pneumatic features, to render the touch more sensitive, and reduce liability to derangement, as well as to give more convenient access to the parts. To this end I make the compressed-air chamber in the form of a marginal trunk entirely outside the bank of keys and surrounding the same on three sides, arrange the valves in this trunk, and operate them by two series of rock-shafts, one crossing the other at right angles and each rock-shaft being provided with a series of crank-arms, the crank-arms of the rock-shafts of one series being extended to close approach to the crank-arms of the other series of rock-shafts, so that any key in descending will strike and depress a crank-arm on one series of rock-shafts and also at the same time a crank-arm on one of the other series of rock-shafts to open two valves in the marginal compressed-air trunk and transmit two pneumatic blasts through suitable pipes to two corresponding punch-operating pistons, all as hereinafter more fully described with reference to the drawings, in which—

Figure 1 is a plan view of my keyboard base, the keys and upper parts being removed. Fig. 2 is a side view, partly in section, of the keyboard. Fig. 3 is a perspective view of one corner of the marginal compressed-air trunk, partly broken away. Fig. 4 is a sectional detail showing the connection between the compressed-air trunk of the keyboard and one of the punch-operating pistons. Fig. 5 is a sectional detail showing a modified form of the pneumatic valve.

In the drawings, Fig. 2, C represents the keys, which rise in succession away from the position of the operator like the keys of a type-writer. The keys bear upon their outer faces the letters and characters which they represent, and the posts of the keys descend through and are guided by a deck-plate D.

Each key-post has on its lower end a button or disk e, Fig. 3; that rests upon the proximate free ends of a pair of right-angular crank-arms a and b, fixed to a corresponding series of rock-shafts. The positions of these

- key-buttons in relation to the crank-arms are indicated by the dotted circles in Fig. 1, where the two series of crank-arms *a* and *b* may be seen projecting toward each other.
- 5 A A A, &c., represent a series of parallel rock-shafts, each of which bears a series of crank-arms *a a a*, rigidly connected to it.
- 10 B B B, &c., represent a series of parallel rock-shafts lying in a plane beneath the rock-shafts A and crossing the same at right angles. Each rock-shaft B has also a series of crank-arms *b b b*, which are bent up slightly at their free ends, as seen in Fig. 2, so as to lie in the same horizontal plane with the 15 crank-arms *a* of the other series of rock-shafts. The free ends of the two crank-arms *a* and *b* of each pair approach each other so closely as to nearly intersect and allow their outer ends to lie beneath the same 20 key-button *c* of a key, as seen in Fig. 3, so that when any key is depressed it will act both upon the arm *a* and arm *b* of any pair and so rock the two shafts A and B, to which they are respectively attached.
- 25 The outer ends of the rock-shafts A and B are journaled in a marginal frame *T T' T²*, which surrounds the bank of keys on three sides and lies outside of the same, as seen in Fig. 1. This marginal frame is made hollow 30 on its upper side to form an air-trunk in which is maintained constantly a supply of compressed air by means not necessary to be described. The top *t* of this trunk is removable for the purpose hereinafter described.
- 35 Through the bottom of this trunk-frame are formed a series of holes *o*, Fig. 4, each of which communicates with one end of a passage-way or pipe *E*, leading to a small cylinder *F*, in which plays a piston *e*, which is 40 raised and lowered by a blast of air and which piston in its movement actuates one of the punches which perforates the paper record-strip. Only one of these connections is shown in Fig. 4; but it will be understood 45 that there is one for each rock-shaft in both of the series.
- At the point where each rock-shaft enters the air-trunk it is provided with a rigidly-connected flap-valve *v* or *v'*, which rests 50 above and closes the top of the air-passage *o* and is held tightly down thereupon by pneumatic pressure. When, however, the rock-shaft is rocked by a depression of a key, this flap-valve is raised and the compressed air in 55 the trunk *T T' T²* passes down through the outlet *o* and acting through the pipe *E* lifts the piston *e* and operates a punch. As two rock-shafts are simultaneously rocked by the 60 depression of any key intersecting a pair of crank-arms *a* and *b* it will be remembered that two punches are simultaneously operated to perforate the paper strip in the pre-determined way to indicate the letter or character to be punched, the relative posi-

tion of the holes on the strip of paper serving 65 to give the selective or differentiating effect in accordance with the known principles of the monotype system.

I prefer to use the flap-valve, as shown in Figs. 1, 2, 3, and 4, as this makes a quick 70 opening and a tight closing, and its closing power is supplied by the air-pressure above it without the need of springs. I have shown, however, coil-springs *s* on the rock-shafts, which may be of value in several 75 ways. Thus, for instance, in Fig. 5 I show instead of a flap-valve a rotary plug-valve *v'*, turning in a seat in the trunk, and with this form of valve where the air-pressure will not effect the closing the spring would be essential. The springs, moreover, may be of 80 value with the flap-valve either to hold them more tightly closed or the spring might be arranged with the flap-valve, so as to partially antagonize the air-pressure, and thus 85 permit me to use a high pressure of air for operating the punches and yet enable the keys to open the flap with a light and sensitive touch. I therefore do not confine my 90 invention to the particular construction and arrangement shown and described either of the valves or the other parts of my keyboard, as they may be varied in many respects without departing from my invention 95 as expressed in the claims.

As shown, two side trunks *T' T²* are used for the B series of rock-shafts. This is merely to enable me to more widely separate the valves *v'*, and thus get more room to make the necessary connections for the air-pipes below, for by putting the side valves alternately at opposite ends of the rock-shafts B the valves on the two sides may be more widely separated. It is obvious that all the valves may be at the same ends of the 105 rock-shafts and that this alternation of valves and wider spacing may be employed with both series of rock-shafts.

B², Fig. 1, is a short rock-shaft receiving the thrust of but one key in the lower row, 110 this being known to those conversant with the machine as the "justifying-space key."

B' is a dummy rock-shaft in alignment with *B²* and which shaft *B'* opens no valve, but is merely employed to bring to certain of 115 the lower keys the same resistance as the others, so as to give a uniform touch.

By placing the valves *v v'* in the marginal trunk outside the vertical range of the bank of keys there is a great simplification and cheapening of the keyboard, and as the top *t* of the trunk is removable access to the valves for cleaning and repairs is always easily and quickly effected.

Although I have shown and described my 125 keyboard as designed for the monotype perforating-machine, I wish it to be understood that I do not confine it to this use, but may

employ it generally wherever a manually-operated keyboard may be employed for a selective action.

I claim—

- 5 1. A pneumatic keyboard, comprising a series of depressible keys, a series of subjacent and parallel rock-shafts operated upon by the keys, an air-trunk arranged outside of the bank of keys, and valves in the trunk connected to and operated by the rock-shafts.
- 10 2. A pneumatic keyboard, comprising a series of depressible keys, two series of subjacent rock-shafts arranged crosswise in relation to each other, a rock-shaft of each series being arranged to be operated upon by each key, a marginal air-trunk arranged outside the bank of keys and valves in the air-trunk connected to and operated by the rock-shafts.
- 15 3. A pneumatic keyboard, comprising a series of depressible keys, a series of subjacent and parallel rock-shafts having crank-arms arranged beneath the keys, an air-trunk arranged outside the bank of keys and valves arranged in the trunk connected to and operated by the rock-shafts.
- 20 4. A pneumatic keyboard, comprising a series of depressible keys, two series of subjacent rock-shafts arranged crosswise in relation to each other, the rock-shafts of the two series having crank-arms, with the crank-arms of one series extending to proximity with the crank-arms of the other series at points within range of simultaneous action thereupon by the keys, a marginal air-trunk arranged outside the bank of keys, and valves in the trunk connected to and operated upon by the rock-shafts.
- 25 5. A pneumatic keyboard, comprising two crossed series of rock-shafts with valves operated thereby, and a bank of keys superposed over the rock-shafts, each key being arranged to operate upon a rock-shaft of each series.
- 30 6. A pneumatic keyboard, comprising a bank of keys and a marginal air-trunk outside the vertical range of the bank of keys, valves in the air-trunk and means for operating them by the keys.
- 35 7. A pneumatic keyboard, comprising a series of depressible keys, a series of subjacent parallel rock-shafts operated upon by

the keys, an air-trunk arranged outside the bank of keys and having a plurality of outlets and valves fixed to the rock-shafts and controlling said outlets.

8. A pneumatic keyboard, comprising a series of depressible keys, a series of subjacent parallel rock-shafts operated upon by the keys, an air-trunk arranged outside the bank of keys, valves arranged in the trunk and operated by the rock-shafts, and springs for turning the rock-shafts.

9. A pneumatic keyboard, comprising a series of depressible keys, a series of subjacent parallel rock-shafts operated upon by the keys, an air-trunk arranged along the margin of and outside the bank of keys, valves arranged in the air-trunk, and a detachable cover for the trunk.

10. A pneumatic keyboard, comprising a series of depressible keys, a series of subjacent and parallel rock-shafts operated upon by the keys, a marginal compressed-air trunk with valves operated by the rock-shafts, the valves being arranged at opposite ends of the alternating rock-shafts.

11. In a key-actuated mechanism, a bank of keys and subjacent rock-shafts each having a plurality of lateral arms adapted to receive the thrust of the keys, said rock-shafts being adapted to actuate movable parts contiguous thereto.

12. In a pneumatic keyboard, the combination of a key-bank, an air-pressure chamber contiguous thereto, a series of valves each controlling an outlet from said air-pressure chamber, and means for simultaneously and selectively operating a plurality of said valves by the depression of a single key.

13. In a key-actuated mechanism, the combination of two series of rock-shafts and means for selectively operating any shaft of one series simultaneously with any shaft of the other series, said shafts being adapted to actuate movable parts contiguous thereto.

14. In pneumatic keyboard, the combination of a valve, a series of keys, and means connecting said valve with said keys whereby the valve may be operated by any key of the series.

ARTHUR J. WADSWORTH.
